DEVICE FOR REGULATING THE HEIGHT
OF MASHER ARMSRobert C. Schock, New Rochelle, N. Y., assignor
to Schock, Gusmer & Co. Inc., Hoboken, N. J., a
corporation of New Jersey

Application March 2, 1944, Serial No. 524,762

1 Claim. (Cl. 259—135)

This invention relates to mash or lauter or the like machines and more particularly to the mechanism for raising and lowering the masher arms utilized to support knives or the like used in the treatment of the mash.

At the present time hydraulic mechanism has been generally used for this purpose but this has many disadvantages.

The invention has for an object to provide mechanism to take the place of such hydraulic mechanism and to provide a more efficient mechanism having the advantages hereinafter pointed out.

The invention consists of a mechanism for the raising or lowering of arms for the knives, which mechanism embodies a centrally disposed rotating shaft supported at its lower end upon the foundation, extending upwardly through the bottom of the tank to above the level of the mash in the tank, around which shaft an upper sleeve, in turn supporting the arms, rotates, which sleeve is raised or lowered by another and lower sleeve extending through the bottom of the tank, below which bottom, mechanism for raising or lowering the second sleeve is provided, both sleeves being capable of vertical shifting along the central shaft, while it is rotating. By the central shaft acting as the central member, the other parts described surround the same while disposed at different parts of its length, whereby a structure simple in mechanical installation, access, repair, etc. results. Most important is the direct mechanical action resulting, always preferable to those requiring hydraulic controls.

The central shaft is rotatable and non-shiftable, the upper sleeve is rotatable and shiftable, the lower sleeve is non-rotatable and shiftable, and the bottom of the tank is non-rotatable and shiftable.

The invention will be further described, an embodiment thereof pointed out in the drawing and the invention will be finally pointed out in the claims.

In the accompanying drawing,

Fig. 1 is a central vertical section of my improvement,

Fig. 2 is a horizontal section taken on lines 2—2 of Fig. 1, and

Fig. 3 is a diagrammatic view.

Similar characters of reference indicate corresponding parts.

Referring to the drawing, the central rotating shaft 10 is supported upon the foundation 12 through the intermediary of a bearing support 11. Upon this support 11, vertical standards 13 are also supported, which in turn support the bot-

tom 15 of the tank. Such tanks are well known and the drawing simply indicates in dotted lines the usual tank. Preferably four standards 13 are employed although this number may vary. The bottom 15 has a central opening 16 and upon the bottom a plate 17 rests, which also has a central opening 18, and upon the plate 17 a cylindrical support 19 rests which has internal liquid proof packings or bearings 20. Supported by the lower side of the plate 17 is a casing 21 having an interior flange 22 with an internal gland 22a and having a bottom plate 23, which has a cutout 24 to permit the placing of a friction bearing 25. The plate 23 has a central opening 26, of substantially the same diameter as the diameter of the flange 22. The bottom plate 23 of the casing supports a depending cylindrical casing 27, the bottom of which has a central opening 28, substantially the diameter of the shaft 10, with the provision of a liquid or oil leakage proof seal 30. Within the casing 21 is a sleeve 29 which extends upwardly through the tank opening, and then supports the upper sleeve 43.

Within the casing 21 is a worm gear 31 having curved teeth 32 at its periphery meshing with a worm spindle 33, rotated on its axis by any suitable means, as a handwheel or power connection. The worm gear 31 has a hub 34, the bore of which is provided with interior screw threads 36, meshing with exterior screw threads 37 on the exterior of the sleeve 29. The exterior screw threads 37 extend to the lower end of the sleeve 29, where the sleeve almost abuts against the bottom of the depending cylindrical casing 27. The sleeve 29 at its free upper end has an outwardly extending flange 38 and an interior cutout portion 39 for the glands 40. The upper end of the sleeve 29 supports the sleeve 43 through a friction bearing 41, which in turn supports an inverted cup 42, having above it the sleeve 43. The upper sleeve 43 has its bore provided with a longitudinal slot 45, adapted to be engaged by a key 46 secured to the shaft 10. This permits first the upward or downward movement of the sleeve 43 in respect to the shaft 10 and assures the sleeve 43 rotating upon the rotation of the shaft 10.

Suitably secured or cast integrally with the sleeve 43 is a bracket 48, which supports the radial masher arms not shown as well known and which extend from 48a. To operate the devices supported by the masher arms, the lower ends of the supports 48 support an operating shaft 49 which has a conical gearwheel 51, which meshes with a nonrotating conical gear 52 sup-

ported by the cylindrical support 19, which gear 52 has a central bore for the passage of the sleeve 29.

The shaft 10 as seen forms the central member and is free from all load and rests upon the support 11. The load of the masher arms and operating shafts is taken up by the sleeve 29 and in turn by the threads 36 and 37, and these being considerable in number distribute the load per surface area. Such load is supported by the tank 10 and the standards 13, and not by the shaft.

The mash arm or appurtenant mechanism are readily raised or lowered by the operation of the worm spindle 33, and no part of this effort is transposed to the shaft 10. The worm spindle 33 acts as a safety locking device, since it does not rotate upon any downward pressure being applied to the sleeve 29.

Sometimes the masher arm is combined with the shaft 49. These features of masher arm, operating shaft, whether combined or separate, are well known.

The operation of the device is as follows:

The shaft 10 is rotated by suitable means, not shown as known to the art, and the tank being partially filled with its batch of mash, has the mash arm lauter knives, for example, move in a circular path through the mash. When it is desired to remove knives from the batch they are raised above the level of the mash. But this raising and lowering is carried out by a simple mechanical and positively acting mechanism herebefore described instead of by a hydraulic mechanism as heretofore known. This is brought about by the operation of the handwheel, which actuates the worm and the worm gear. The rotation of the gear rotates the screw threaded sleeve and thereby raises the screw threaded sleeve which in turn raises the upper sleeve which supports the mash arms. The lowering takes place by moving the worm in the opposite direction.

The improvement is shown in Figure 3 in which the cooperative parts are shown only diagrammatically, the tank being non-rotatable and ver-

tically non-shiftable, the shaft being rotatable but vertically non-shiftable, the lower sleeve being non-rotatable but vertically shiftable and the upper sleeve being rotatable and vertically shiftable.

It is obvious that various changes and modifications may be made in the details of construction and design of the above specifically described embodiments of this invention without departing from the spirit thereof, such changes and modifications being restricted only by the scope of the following claim.

What I claim is:

In a device for regulating the height of masher arms of mash machines having a tank, the combination of a rotatable and vertically stationary shaft of the same diameter throughout, an upper sleeve surrounding the upper part of said shaft for supporting the mash arms and keyed to the shaft to permit vertical shifting on the shaft and rotation with the shaft, a lower sleeve surrounding the lower part of the shaft non-rotatable in respect to the shaft and vertically shiftable on the shaft and supporting the upper sleeve, both of said sleeves having bores substantially of the same diameter as the diameter of the shaft, and being vertically unsupported by said shaft, external screwthreads surrounding the lower part of said lower sleeve, a worm gear having a bore with interior screw threads meshing with said external screwthreads and having external peripheral screwthreads, a worm for engaging said peripheral screwthreads, a horizontal stationary wall disposed below the upper sleeve and disposed above the worm gear and worm, the shaft and lower sleeve extending from below the wall to above the same, and means below the wall for supporting said worm gear and worm below and on the lower part of the wall, whereby upon the rotation of the worm the mash arms supported by the upper sleeve are raised or lowered without vertically shifting the shaft.

ROBERT C. SCHOCK.
